UNITED STATES PATENT OFFICE.

JOHN S. GULLBORG, OF CHICAGO, ILLINOIS, ASSIGNOR TO ALEMITE DIE-CASTING & MFG. CO., OF CHICAGO, ILLINOIS, A CORPORATION OF ILLINOIS.

DIE-CASTING MACHINE.

Application filed August 1, 1924. Serial No. 729,450.

The present invention relates to die-cast-ing machines.

One of the prominent objects of the in-vention is to provide improved means for 5 transferring the molten metal from the melting pot to the die mold. This improved means comprises a nozzle, the spout of which is dipped below the surface of the molten metal and is then raised up to the dies by a 10 direct upward motion of the nozzle. No horizontal translatory motion of the nozzle is necessary because the nozzle is arranged to discharge into a substantially vertical sprue hole entering the underside of the die 15 mold. Consequently, the entire motion of the nozzle is a simple upward and downward oscillation, by which a high rate of opera-tion of the machine is maintained. The nozzle holds only a small weight of metal 20 compared to the weight of metal in the pot, and consequently by moving the nozzle instead of the pot there is saved a considerable expenditure of power. Moreover, by moving the nozzle, the movement may be rela-tively rapid without the possibility of any 25 surging or agitation of the molten metal which might result from a rapid movement of the pot; also, by the practice of a moving the nozzle there is no difficulty in main-taining the melting pot under continuous 30 uniform heat with a fixed arrangement of burner nozzles.

A further object of the invention is to pro-35 vide improved means for pulling the core pins or other core members from the die molds. According to the present invention I utilize compressed air for obtaining the requisite power for pulling the core pins, and associate with this compressed air 40 mechanism mechanical restraining means for controlling and moderating the action of the compressed air mechanism. This re-straining means prevents the compressed air mechanism from jerking out the core pins 45 with a shock, or from completing the end of the pulling stroke with a shock when the core pins let go. By using compressed air for the core pulling energy instead of mechanical means, such as cam mechanism 50 in the machine, a large amount of energy can be quickly concentrated on the core pins without shock or vibration in the machine and without undesirable stresses in the work-ing parts of the machine.

55 Other objects concerned with the features

of construction of the machine will be ap-60 parent from the following detailed descrip-tion of a preferred embodiment of my in-vention, this preferred embodiment being illus-trated in the accompanying drawing in which:—

Fig. 1 is a side elevational view of the 65 machine;

Fig. 2 is a longitudinal sectional view of 70 the machine;

Fig. 2^A is a fragmentary detail section of 75 a part of Fig. 2;

Fig. 3 is a top plan view of the same;

Fig. 4 is a bottom plan view of the table 80 viewed from the under side;

Fig. 5 is an elevational view of the end of 85 the machine containing the metal pot and metal conveying nozzle; and

Fig. 6 is a similar view of the opposite end 90 of the machine;

Fig. 7 is a vertical transverse sectional view 95 taken on the plane of the line 7—7 of Fig. 2;

Fig. 8 is a similar view taken on the plane 100 of the line 8—8 of Fig. 2; and

Figs. 9 and 10 are plan and vertical sec-tional views, respectively, of the pneumatic 105 core pulling cylinder.

The table of the machine is designated 9 and it will be observed from Fig. 7 that this 110 table has an outer depending flange 9', to which are bolted several of the frame mem bers and appurtenances of the machine.

The table is divided through its length 115 into front and rear halves having medial flanges 10 which are bolted together on the under side of the table (see Fig. 4). Corner legs 11 are secured to the table 9 by bolts 12, (see Fig. 4 and intermediate legs 13 of T section are also secured to the table 9 by 120 bolts 12. Side plates 14 (Fig. 1) are bolted 125 to the left-hand corner legs and to the two intermediate legs 13 on each side of the ma-chine. A pit 15 is formed in the floor or other foundation for accommodating some 130 of the operating wheels and other parts of 135 the machine.

Formed on the upper surface of the table 9 140 are two beveled guides 19, on which moves a reciprocating slide 21 having correspondingly beveled guide members 16 (Fig. 7). An upright supporting face 22 is formed ad-jacent the forward end of the slide 21, and to this face is bolted one section 23 of the die mold (see Fig. 1). The other section 24 145 of the die mold is fixedly supported on the 150

front face of a standard 25 rising from the table of the machine. This standard has lateral flanges which are bolted to the table of the machine, as indicated at 26, and on its 5 front die supporting face has a lower flange 27 against which the lower edge of the die section rests, the upper end of the die section being securely clamped against the standard. Rising from the other end of the 10 table are a pair of spaced standards 29, which are likewise bolted to the top of the table, as indicated at 31. As shown best in Fig. 6, each standard 29 is formed with a boss 32, on the opposite sides of which a pair 15 of links 33—33 are pivoted upon a transverse pivot pin 35. These two links 33 form one arm or link of a toggle link connection between the standard 29 and the reciprocating slide 21. The knuckle of the said toggle 20 is formed by a transverse pivot pin 35 which passes through the upper ends of both links 33, and through a pair of links 36 disposed just inside of the links 33, and also through a central power link 37 which has its eye disposed 25 between the links 36. The lower ends of the links 36 carry a block 38 which receives the threaded shank of an eye-bolt 39. A nut 41 (Fig. 2) screws over the upper end of the eyebolt 39, whereby the eye-bolt can 30 be adjusted up or down relative to the links 36 and locked in position. The eyebolt 39 extends into a clevis opening in a metallic horn or arch 42, being pivotally secured in this clevis opening by a transverse pivot pin 35. The horn or arch 42 is a curved reinforcing member formed integral with the horizontal portion of the slide 21 and the upright die supporting face 22. This 35 arched member reinforces the die face 22 against the pressures transmitted to the die face, and also affords a convenient point of connection between the toggle mechanism and the slide. The toggle mechanism just described is duplicated for the other standard 40 29, as shown in plan in Figure 3. That is to say, the other standard has a similar pair of links 33 connecting with another pair of links 36 and with a downwardly extending power link 37. The links 36 of this 45 latter toggle mechanism have pivotal connection through an eye-bolt 39 with a second curved reinforcing arch 42.

Referring to Figs. 3 and 4, both power links 37 converge together and pass down 50 through a slot 44 in the table 9, for pivotal connection at 45 on opposite sides of a single central rocking lever 46. This lever is pivoted at its inner end on a pivot pin 47 extending through spaced bearing hubs carried 55 on a bearing bracket 48. A main operating shaft 49 extends transversely through the machine below the lever 46 and has its ends journaled in four-arm bearing brackets 51 which are bolted to the legs 11—13, and 60 to the flange 9' and floor 20. Mounted fast

on this shaft is a wheel 52 disposed in close proximity to the lever 46. The face of the wheel adjacent the lever 46 is formed with a cam groove 53 of the configuration shown in Fig. 2. A roller bracket 54 is secured to the 70 side of the lever 46 and this bracket carries a roller 55 which lies in the cam groove 53. The movement of the roller 55 towards and away from the center of the cam wheel 52 rocks the lever 46 and operates the toggle 75 mechanism 33—36—37 to reciprocate the slide 21 towards and away from the stationary die mold 24.

Power is transmitted to the cam wheel through a silent chain 56 this chain meshing 80 with sprocket teeth 57 on the periphery of the cam wheel and being trained up over a relatively small sprocket wheel 58 on a transverse driving shaft 59. As shown in Fig. 4, the shaft 59 is supported at one end 85 in a bearing bracket 61 bolted to the under side of the table, and at the other end is supported in a suitable bearing 62, and has a pulley or driving wheel 63 on its outer end. The means for effecting and controlling the 90 transmission of power to the pulley 63 may be of the same general description as that disclosed in my prior Patent No. 1,322,502. As representative of the manual actuating element for this control mechanism, I have 95 shown an operating lever 70 pivoted to the front of the machine (Fig. 1), and connected through a rod 80 with a lever 90 supported on a control shaft extending back into the machine. A full and complete description 100 of this control mechanism, is contained in this prior patent, and accordingly I shall not go into the details of such control mechanism in the present application.

I shall now describe the operating mechanism for those movable supporting members that carry the upper and lateral core pins, core boxes, or other upper and lateral die members. The opposite side of the cam wheel 52 is provided with another cam 110 groove 64 formed between laterally projecting flanges on the face of the wheel similarly to the cam drum 53, but differing therefrom in that this cam drum 64 is of somewhat elliptical form. Tracking in this cam 115 groove is a roller 65 which is pivotally supported on one end of a rocking lever 66. This lever 66 is pivoted at its intermediate point on a pivot 67 carried on a bracket 68 depending from the under side of the table 120 9. The outer end of the lever projects beyond the end of the machine for pivotal connection at 69 with a pair of links 71 which extend up and have pivotal connection 72 with a vertically reciprocating slide 73. 125 As shown in Figure 6, this slide is guided in a suitable guide block, or between a pair of suitable guide members indicated generally at 74. This guiding means 74 is bolted at 75 to the rear standard 29. The upper 130

end of the slide 73 is bifurcated to have a pivotal connection at 76 with a horizontal rocker arm 77. The left-hand end of this rocking lever 77 is pivoted at 78 to a short link 79 pivotally connected at 81 to the left-hand pedestal 29 of the frame; this link 79 permitting a slight lateral motion of the pivot 78 under the rectilinear throw of the pivot 76. The other end of the rocking lever 77 has pivotal connection at 82 with a pair of links 83 connecting at 84 with a crank arm 85 keyed to the operating shaft 86. A cross member 87 is bolted to the upper ends of the standards 29, and this cross member has an upwardly extending bearing extension 88 in which is journaled one end of the shaft 86. The crank arm 85 is keyed to the shaft 86 outside of the bearing bracket 88. The shaft 86 extends across the top of the machine and has bearing support adjacent its other end in a bearing extension 89 projecting upwardly from the standard 25 (Fig. 5).

Outside of the bearing extension 89 a lever 91 is rigidly keyed to the shaft 86, and has a pivotal connection at one end through the parallel links 92 with a vertically moving slide 93. This slide is confined in a vertical guideway of the standard 25 by guide members 94 which are bolted at 95 to the standard 25. Where it is desired to use a vertically moving core pin, or an upper die member in conjunction with the die molds 23 and 24, this core pin or die member is preferably mounted to move directly with the vertical reciprocating motion of the slide 93.

As shown in Figures 2 and 5, an adjustable plate 96 is supported between the slide 93 and the adjacent wall of the vertical standards 25, this plate having an arm 96' extending laterally through a slot in the central upper part of the standard 25. A link 97 is pivotally connected to the upper side of the arm 96' by a bolt 98. An extensible arm 99 is secured to the outer end of this link 97 by the bolt 101. The bolt 101 has a flanged head on its lower end engaging in a slot or T-shaped recess 101' in the arm 99, whereby the arm can be slid backward or forward or rotated and thereafter clamped in the desired position relative to the links 97. This arm 99 is adapted to carry the upper core pin or other upper die parts adapted to cooperate with the die molds 23 and 24. Vertical adjustment of the core pin or other die part is conveniently effected by securing a threaded hub 103 to the face of the adjustable plate 96 and screwing adjusting screws 104 through bridge members 105 on the slide 93, these screws 104 being adapted by their manipulation, to shift the block or hub 103 and plate 95 relative to the slide 93. After each adjustment the screws 105 may be locked in the bridge members 105 by lock nuts 107.

Laterally moving core pins or die parts

are carried by two laterally reciprocating plungers 108—108. These slide in cylindrical boxes 110 bolted to the standard 25. The upper sides of the guide boxes 110 are slotted for receiving the lower ends of bell crank levers 120 adapted to simultaneously actuate the two plungers 108—108. The lower ends of the levers 120 have cylindrical or spherical ends which engage in correspondingly formed recesses 120' in the upper sides of the plunger. The levers 120 are pivoted on stationary pivot pins 102 secured to the standards 25, and the upper ends of the levers have drilled blocks 100 swiveled thereto. Rods 90 having their upper ends swiveled in eyes 93' on the upper part of the slide 93, extend down through these swiveled blocks 100 and have their lower ends threaded for the reception of lock nuts on both sides of the blocks 100. By adjusting these nuts 80 along the rods 90, either plunger 108 may be adjusted inwardly relative to the vertical position of the slide 93.

The lateral core pins or die parts are supported by an arrangement of links 97' and supporting arms 99' on each side of the machine, similarly to the mounting of the vertical core pin. Each link 97' is secured to the outer end of its respective plunger 108 by a bolt 98', and each supporting arm 99' has a slidable and rotatable connection with the outer end of its respective link through a pivot bolt 101'. The vertical and lateral core pins are rigidly held in the clamping grooves 99' in the inner faces of the supporting arms 99 and 99', having a wide range of transverse and longitudinal adjustment in this supported relation through the swinging and extending of the links 97 and arms 99'.

It will thus be seen that the timed reciprocation of the slide 93 is operative to thrust inwardly into the die opening upper and lateral core pins or die parts and to remove these die parts after the air pressure is off of the metal in the die mold. The operating connections which I have heretofore traced for this slide 93, through the shaft 86, and elements 85—83—77—71—66 and 64 to the eccentric groove in the cam wheel 52, merely operate to place the core pins or die parts between the two main dies in completing the die mold, and to control the rapidity and possibly the timing under which these core pins or die parts are withdrawn. The actual energy required to withdraw the core pins, etc., from the mold is derived from pneumatic mechanism which I shall now describe the above mechanical connections governing and controlling the operation of this pneumatic mechanism.

Referring again to Fig. 5, the lever 91 is extended to the other side of the shaft 86 for pivotal connection with a clevis 201 which has adjustable connection through the

4
nuts 202 with the upper end of a long piston rod 203. This rod extends down to a pneumatic cylinder 204 supported on one side of the table or frame 9. As shown in Figs. 9 and 10, this rod passes down through a gland packing 205 in the cylinder head 206 and has connection with a piston 207 in the cylinder. The cylinder is suspended from a cross trunnion 208, the ends of which have bearing support in brackets 209 bolted to the side of the table. This permits a limited pivotal movement of the cylinder and avoids all necessity of accurate alignment, etc.

Compressed air is admitted to the upper end of the cylinder through a pipe 211 which extends from a suitable valve box 212, bolted to the inner side of one of the brackets 209. Compressed air is supplied to this valve box through a pipe 213 leading from any suitable source, such as the source of compressed air for expelling the metal from the tilting nozzle, which I shall presently describe. The valve element, not shown, is connected to a long valve rod 214 extending back towards the main operating shaft 49 (Fig. 4). Here it has pivotal connection with a lever 215. One end of this lever has a pivotal mounting on a suitable fixed pivot and the other end supports a roller 216 (Figs. 4 and 7) which tracks on a cam 217 mounted on the shaft 49. A suitable spring holds this roller against the cam face. In one position the shiftable valve in the valve box 212 admits compressed air to the top of the piston, and in the other position vents this end of the cylinder to atmosphere.

In the operation of the machine the cam groove 64 is so timed relative to the cam groove 53 in the cam wheel 52 that the slide 93 is moved downwardly and the vertical and lateral die parts are thrust inwardly into cooperation with the stationary die mold 24 before the cam groove 53 actuates the toggle links 36-33 to thrust the moving die mold 23 into cooperative engagement with the stationary mold 24. During the time that the slide 93 and its associated core pins or die parts are being moved to their positions between the die sections under the mechanical actuation of the roller 65 tracking in cam wheel groove 64, the piston 207 is being drawn up in its cylinder 204. The cam 217 is at this time holding the roller 216 and lever 215 with the valve element in the valve box 212 in position to vent the upper end of the cylinder. Consequently, the piston moves through the upward stroke unrestrictedly.

In the operation of withdrawing the core pins or like parts from the die opening, the rotation of the cam 217 will rock the lever 215 and oscillate the compressed air valve in the valve box 212 to admit compressed air to the upper area of the piston. Substantially simultaneously therewith the eccentric groove 64 will begin a downward throw of

the lever 66, which, acting through the connections 71-77-83-85 and 86 will tend to raise the slide 93 and withdraw the core pins or like parts. The greater rapidity of action of the piston 207 in the cylinder 204, however, results in this piston imposing its energy on the slide 93 before the mechanical means above mentioned, so that the effort of actually cracking the core pins loose from the die opening is performed by this compressed air cylinder 204. The mechanical connections comprising the cam groove 64 and roller 65 follow the action of the air cylinder and govern the action thereof by preventing the air cylinder from jerking the core pins out with a shock and possibly breaking some of the parts. The air cylinder may perform the entire operation of withdrawing the core pins all the way, or the valve in the valve box 212 may be timed to admit air sufficiently long to cause the piston to free the core pins from the die opening, after which the mechanical means 64-65, etc. may take up the duty of retracting the core pins to the outer limits of their strokes.

The castings are adapted to be displaced from the movable die section 23 by knock-out pins thrust forwardly through the die section 23 when the slide is drawn backwardly to separate the dies. I shall now describe the mechanism for operating these knock-out pins. A shaft 109 is supported for reciprocation in two spaced hubs 111 formed at opposite ends of a supporting bracket 112 which is bolted to the slide 21. The forward end of this shaft is arranged to support a plate 113 adapted to carry the knock-out pins 114. Any number of knock-out pins may be carried by the plate 113, and these pins may have different groupings in accordance with the requirements of the particular die, the arrangement in Figure 2 being merely typical. As shown in this figure, two knock-out pins 114 are carried by the plate 113, being secured thereto by nuts 115. A clamp 116 is secured around the shaft 109 intermediate the hubs 111, and this clamp has pivotal connection through a pin 117 with a pair of links 118 engaging on opposite sides of the clamp hub. These two links 118 connect through pivot pin 119 with one arm of a bell crank lever 121. The pivot pin 43 which extends through the eye-bolts 39 of the toggle mechanism also extends through the hub of the bell crank lever 121, the latter being positioned between the two arched reinforcing members 42. The other arm of the bell crank lever consists of a socket 122 having an arm or rod 123 pinned therein. A pivot 124 connects the upper end of this arm with two spaced links 125, which extend up and engage over stud pins 126 projecting from a block 127. This block is slidably supported on a threaded

rod 128 supported at its ends in hubs 129 depending from the centers of the cross bars 87 and 131. The ends of the bar 131 are formed with semi-circular clamp portions for embracing the under sides of the brace rods 131', this bar being clamped to these rods by upper cooperating clamp sections 132 which engage over the tops of the shafts and are bolted to the bars 131. Lock 10 nuts 133 secure block 127 at any desired point along the threaded rod 128.

In forward reciprocation of the slide 21 the bell crank lever 121 will be oscillated in a clockwise direction, and this motion of the bell crank lever thrusts the shaft 109 rearwardly through the links 118. When the slide is reciprocated backwardly to separate the dies this bell crank lever is oscillated in a counterclockwise direction, and consequently the shaft 109 is thrust forwardly towards the die section 23, so that the knock-out pins 114 will displace the die casting from the die opening. It will be observed that at the beginning of this die separating motion the pivot 119 is relatively close to the horizontal plane of the pivot 43, whereby the initial pulling motion on the links 118 and shaft 109 is at a relatively short, powerful radius arm. Thus, the initial movement of the knock-out is very slow. Thereafter, the pivot 119 revolves up to a more effective lever arm, with a result that the motion of the knock-out pins is gradually accelerated. This gradually accelerating motion of the knock-out pins avoids any possibility of the pins breaking the castings in displacing them from the die section 23. Any desired length of stroke or timing of the knock-out pins 114 may be obtained by shifting the pins relative to the plate 113, or by shifting the clamp 116 on the shaft 109, or shifting the block 127 along the threaded rod 128.

The metal pot from which the molten metal is transferred to the dies is designated 134, and is located at the left-hand end of the machine (Fig. 2). This pot is contained within the casing 135 which is suspended in an opening 136 (Fig. 4) in the table 9. The casing 135 and pot 134 are capable of being slid endwise out of the slot-like opening 136. A rod or shaft 130 extends crosswise between the end legs 11 and supports rollers 140 on which the casing can be slid out of the opening 136. The casing 135 is lined with a refractory material 137, this heat refractory material being spaced sufficiently from the walls of the pot 134 to leave a combustion chamber area 138. Any suitable arrangement of burner nozzles 139 discharges into this combustion area for heating the pot 134. The pot 134 is removably suspended in the casing 135 by the engagement of a flange 141 on the pot over a supporting flange 142 on the inner wall of the casing.

The top of the pot is closed by a cover 143. Convenient access is afforded to the interior of the pot through a hinge door or cover 144.

The metal is transferred from the pot 134 to the dies by a nozzle 145 which is first submerged below the level of the molten metal in the pot 134 for receiving a charge, and is then raised up out of the molten metal into communication with the molds for transferring its charge of metal into the dies 75 under compressed air. The nozzle is preferably of the general form illustrated in Figure 2, having an expanded ladle portion at its lower end and provided with a conical nozzle tip 146 at its upturned end, for re-

ception in a conical socket at the bottom of the sprue hole passing up to the die opening. This end of the nozzle is adapted to be raised and lowered through an opening 147 in the cover 143. The other end of the nozzle extends up out of the pot through an opening 148 in the cover 143, and is bolted or otherwise secured to the cross member 149 of a yoke 151. A plug 152 tightly closes the upper end of this nozzle, the under side of 80 this plug having an annular flange snugly fitting in an annular recess in the upper end of the nozzle, and also having a shank provided with beveled annular grooves. Air is admitted to the upper end of this nozzle 85 above the level of the metal therein through a pipe 153 entering the nozzle laterally, as shown in Figure 2. The two arms of the yoke 151 extend back and have pivotal connection on a common axis through pivot pins 100 154 supported in the upper hub ends of a yoke 155 (see Fig. 5). This yoke 155 has pivotal support at its lower end on a transverse pivot shaft 156 extending through spaced hubs on the bottom of the yoke 155 105 and through an adjustable bearing 157. The bearing 157 has a screw threaded shank 150 which extends through the lateral arm of a fixed bracket 160 secured to the frame of the machine. The bearing 157 is vertically adjustable in the bracket 160, being locked in any adjusted position by lock nuts 170 screwing over the threaded shank 150. A screw 159 passes through a suitable opening in the center of the yoke 155 and receives an 110 adjusting nut 161. As shown in Fig. 2A, the inner end of this screw is provided with a pivot lug 180 which is pivoted to a fixed bracket arm 190 extending from the bracket 160. The inner face of the yoke is provided 115 with a recess 158 concentric with the screw 159 and a spring 162 confined within this recess bears against the pivot lug 180, thus swinging the yoke 155 outwardly against the adjusting nut 161. The vertical adjustment 120 of the bearing 157 and the horizontal pivotal adjustment of the yoke 155 affords any combination of adjustments for shifting the nozzle tip 146 horizontally or vertically to cause it to accurately register with the sprue 125 130

- opening of the dies or to vary the pressure between the nozzle and the sprue opening. The nozzle 145 is raised and lowered through the operation of a pair of levers 163, each of which is riveted to a plate 164 forming part of a relatively long tubular hub 165. Both hubs 165 have bearing support upon a transverse shaft 166, supported at its ends in the lateral frame bars 14. Riveted or bolted to the pair of levers 163 is a single central lever arm 168. The other end of this central lever has a pivot 169 on which is mounted a roller 171 tracking in the cam groove 53 of the cam wheel 52. The single cam track 53 on the cam wheel thus operates to simultaneously rock the lever 46 downwardly for sliding the die sections together, and to rock the lever arm 168 downwardly for raising the nozzle 145 up against the dies. The cam grooves 53 and 64 and the arrangements of the levers 46, 66 and 168 is such that the laterally moving and vertically moving die parts are first presented to the die opening by the movement of the die mounting arms 99 and 99'; the die molds 23 are then brought together and immediately thereafter the nozzle 145 is raised to the sprue opening 145² in the bottom of the completed die mold.
- The upward motion of the lever arms 163 is transmitted through a pivot shaft 172 connecting with an individual link 173 for each lever arm. As shown in Figure 8, the lower end of each link 173 is bifurcated to engage on opposite sides of its respective lever arm 163. A long threaded bolt 174 screws down in the upper solid portion of the member 173, and receives a lock nut 175 screwing down on the top of the member 173. This threaded connection affords an adjustment for shortening or lengthening the links which raise the nozzle 145. A heavy compression spring 176 is confined between the bottom of an upper coupling member 177 and a washer 178 on the rod 174. A nut 179 threads over the lower end of the bolt 174 and provides means for shifting the washer and adjusting the pressure of the spring 176. The upper end of each bolt 174 has a loose sliding fit in the upper coupling member 177. A transverse pin 197 passing through each bolt 174 and engaging in a slot 198 limits the upward motion of the coupling member 177 along the bolt. The upper end of each coupling member 177 is apertured to fit over a heavy stud 182 projecting laterally from the yoke 151. By virtue of the telescopic engagement of the bolts 174 in the coupling members 179, the nozzle outlet 146 is forced against the sprue hole of the dies under the combined pressure of the springs 176-176, so that a close pressure joint is secured between the nozzle and the sprue hole which will be tight against the high air pressure admitted to the nozzle.

The compressed air pipe 153 extends forwardly to an elbow 184 which connects with a laterally extending pipe 185 (Fig. 3). This pipe in turn connects through another elbow 186 with another forwardly extending section of pipe 187. This pipe connects through an elbow 188 with a laterally extending pipe 189. The axis of the elbow 186-188 and pipe 187 is in the same vertical plane with the axis of the pivot pins 154, 75 so that in the upward and downward motion of the nozzle 145 a slight rotation may occur in the pipe couplings and thus accommodate the up and down motion of the pipe 153. The pipe 189 communicates with a 80 valve box 191 supported on the side of the machine. Air under pressure is supplied to this valve box through a pipe 192. The valve element may be of any conventional design, and is actuated by valve stem 193 85 extending out of the valve casing and having pivotal connection through an arm 194 with a vertical lever 195.

This lever is pivoted to the frame of the machine on a cross shaft 196 (Fig. 5). Under the table top of the machine this shaft carries a depending arm 197 which has connection with an operating rod 198 (Fig. 1). This rod has pivotal connection with a lever 199 pivotally connected at its other end to the frame. A roller 200 tracks on a cam 221 on the main operating shaft 49.

In the normal cycle of the machine this cam 221 will open the valve 191 after the dies have been closed and after the nozzle 145 has been pressed up into firm engagement with the sprue hole of the dies. The blast of compressed air into the other end of the nozzle will force the molten metal from the nozzle into the die opening in a manner well known to those skilled in the art. At a further step in the cycle the cam will permit counter movement of the rod 198 and close the valve 191, shutting off the compressed air supply and venting the nozzle to atmosphere so that the nozzle can be drawn down away from the sprue hole.

For protecting the operator against molten metal which might be blown through crevices or openings in the dies, I have provided a shield 224 which automatically descends and surrounds the dies prior to the metal being blown into the die opening. I have also provided means whereby the valve 191 is incapable of opening to admit compressed air to the nozzle 145 until the shield is entirely down in its protecting position, and whereby the raising of the shield compels closing of the valve and venting of the nozzle to atmosphere before the dies are exposed.

This shield comprises front and rear duplicate sections 224 and 224' of sheet metal, having inwardly turned ends as shown in plan in Fig. 3. Each section has corner

guides 225 which slide on pairs of vertical guide rods 226 supported on the front and rear sides of the machine. The upper ends of these guide rods are joined by braces 227 and 228.

Extending upwardly from the lateral corners of each shield section are rods 229, and adjustably mounted on these rods are bars 231, one individual to each shield section. A bail member 232 is attached at its ends to these bars, and extends upwardly between the braces 227. Long operating levers 233 along the front and rear of the machine have their ends operatively connected to this bail 232 for raising and lowering the shield. Each of these levers is pivoted at 234 on a standard 235 projecting upwardly from the standard 87. A counterweight 236 on the outer end of each lever balances the weight of the shield.

The shield is automatically raised and lowered in proper timed sequence in the cycle of the machine through the instrumentality of two cams 237 on the main operating shaft 49 (see Fig. 7). Cam rollers 238 track on these cams, each of these rollers being pivotally supported on levers 239. As shown in Fig. 1, these levers curve over the top of the shaft 49, being pivoted to the frame of the machine at their lower ends and supporting the rollers 238 at intermediate points. The ends of the levers have pivotal connection with vertical operating rods 241 which extend up through openings in the table of the machine and pivotally connect with the levers 233.

Referring to Fig. 1, it will be noted that the lever 195, which operates the air valve 191 for blowing the metal into the die opening, has a roller 243 pivoted at its upper end. This roller is adapted to track on a vertical rail 244 secured to the guide lugs 225 at the side of the front shield section. The upper end of the rail is sloped inwardly as indicated at 244' so that the roller 243 will be cammed back onto the outer side of the rail in the ascension of the shield. When the shield is in the position illustrated in Fig. 1 the lever 195 is positively held against surging movement to the right for opening the valve 191, and at such time it is impossible for the valve to be opened, either accidentally or intentionally. After the shield has been brought down to its lower protecting position, concurrently with the closing of the dies, the roller 243 rides off the upper end of the rail 244. Subsequent to this, the thrust imparted to the rod 198 under the actuation of the cam 221 finds the lever 195 free to swing and open the valve.

In the raising of the shield, if the valve has not already closed the sloped end 244' of the rail will cam the roller 243 backwardly and positively close the valve. It will be

understood that this "closing" of the valve 65 shuts off the supply of compressed air to the nozzle, and vents such quantity of compressed air as remains therein to the atmosphere.

I do not intend to be limited to the particular details herein shown and described.

I claim:

1. In a die casting machine, the combination of die mechanism, a relatively stationary metal pot, a nozzle dipping in said pot, 75 said nozzle having upwardly turned ends, one of said ends having a compressed air connection, an upwardly pointed nozzle spout at the other end of said nozzle, means for moving said nozzle relative to said pot to 80 bring said nozzle spout into communication with the under side of said die mechanism for transferring the molten metal thereto, and spring means cooperating with said last named means for holding said nozzle spout 85 in resilient engagement with said die mechanism.

2. In a die casting machine, the combination of die mechanism, relatively stationary metal pot, a nozzle of substantially U-shaped 90 form dipping in said pot, means for admitting compressed air into one leg of said nozzle, an upwardly opening nozzle spout at the upper end of the other leg, power means for moving said nozzle to move said nozzle 95 spout up into communication with the under side of said die mechanism, and spring means between said power mechanism and said nozzle.

3. In a die casting machine, the combination of die mechanism, a relatively stationary metal pot, a nozzle having an end adapted 100 to be swung from one position to another to transport metal from said pot to said die mechanism, a pivot for said nozzle, and means for adjusting said pivot in a plurality of planes.

4. In a die casting machine, the combination of a molten metal container, a nozzle having an end adapted to be swung from 110 one position to another to transport metal from said container to the die mechanism, a relatively fixed pivot about which said nozzle has motion, and means for adjusting said relatively fixed pivot vertically and 115 horizontally.

5. In a die casting machine, the combination of a molten metal container, a nozzle having an end adapted to be swung from 120 one position to another to transport metal from said container to the die mechanism, a relatively fixed pivot relative to which said nozzle has motion, means for adjusting the position of said relatively fixed pivot horizontally, and means for adjusting the 125 position of said pivot vertically.

6. In a die casting machine, the combination of a molten metal container, a nozzle

adapted to transport metal from said container to the die mechanism, a first pivot associated with said nozzle, a second pivot, a link between said pivots, means for adjusting said pivot in one plane, and means for adjusting said first pivot in another plane.

7. In a die casting machine, the combination of a molten metal container, a nozzle adapted to transport metal from said container to the die mechanism, a pivot about which said nozzle is adapted to swing, a second relatively stationary pivot, a link connecting said pivots, means for adjusting one of said pivots vertically, and means for adjusting the other of said pivots horizontally.

8. In a die casting machine, the combination of a molten metal container, a nozzle adapted to transport metal from said container to the die mechanism, and power means for moving said nozzle, said power means comprising a pair of telescopic members, and a spring cooperating with said members for transmitting a yieldable pressure to said nozzle when the latter is in communication with the die mechanism.

9. In a die casting machine adapted to receive die mechanism, the combination of a molten metal container, a nozzle dipping in said pot, and means for moving said nozzle from said pot into communication with the die mechanism, said means comprising a yieldable connection for yieldably pressing said nozzle in communication with said die mechanism, and means for adjusting the pressure of said yieldable connection.

10. In a die casting machine adapted to receive die mechanism, the combination of a relatively stationary metal pot, a nozzle dipping in said pot, means for moving said nozzle in a substantially curved path from said pot into communication with said die mechanism, and means for adjusting the limit of movement of said nozzle.

11. In a die casting machine, the combination of die mechanism, a relatively stationary metal pot, a nozzle dipping in said pot, power means for moving said nozzle in a substantially curved path from said pot into communication with said die mechanism, and means for adjusting one limit of throw of said nozzle.

12. In a die casting machine, the combination of die mechanism, a relatively stationary metal pot, a nozzle dipping in said pot and being of U-shaped form, means for admitting compressed air to one leg of said nozzle, an upwardly opening nozzle spout at the end of the other leg, an operating lever, means for rocking said lever, a link connecting said lever with said nozzle, said link comprising two telescopic sections, and a spring cooperating with said telescopic sections to yieldably hold the nozzle spout

in communication with the die mechanism.

13. In a die casting machine, the combination of means for receiving the die mold, a relatively stationary metal pot, a metal conveying nozzle adapted to fit into said pot, an arm supporting said nozzle, a pivot at one end of said arm, a relatively stationary pivot, a link connecting said pivot, means for adjusting said relatively stationary pivot, means for adjusting said link, a power operated lever, a link connecting said lever with said nozzle, means for adjusting the length of said last named link, and means for transmitting a yieldable pressure to said nozzle through said last named link.

14. In a die casting machine, the combination of die receiving mechanism, a metal pot, a metal conveying nozzle dipping in said pot, an operating lever, a link connecting said lever with said nozzle, resilient means disposed about said link for urging the nozzle into cooperation with said die mechanism and means for adjusting the length of said link.

15. In a die casting machine, the combination of means for supporting die mechanism comprising a reciprocating slide for moving the die parts together, a molten metal pot, a nozzle for conveying the metal from said pot to the die mechanism, actuating mechanism for said slide comprising a cam follower, means for adjusting said mechanism to vary the stroke of said slide including a screw and an element threaded thereon connected to said latter mechanism, actuating mechanism for said nozzle comprising a second cam follower, and an operating member having a cam groove cooperating with both of said cam followers.

16. In a die casting machine, the combination of die supporting mechanism comprising a reciprocating slide, toggle links for actuating said slide, means for adjusting said toggle links to vary the stroke of said slide including a screw connection associated with said slide, a relatively stationary metal pot, a nozzle for transferring metal to the die mechanism, a lever for actuating said nozzle, a power wheel having a cam groove in the lateral face thereof, a cam follower associated with said toggle links for operating the same, said cam follower engaging in said cam groove, and a second cam follower engaging in said cam groove for operating said lever.

17. In a die casting machine, the combination of die supporting mechanism comprising a reciprocating slide, a metal pot, a nozzle for transferring metal from said pot to the die mechanism, a second die supporting member, operating mechanism for said slide comprising a cam follower, operating mechanism for said nozzle comprising a cam follower, operating mechanism for said second die supporting mechanism comprising

a cam follower, and driving means comprising cam means cooperating with said three cam followers.

18. In a die casting machine, a molten metal container, a nozzle having one end pivotally mounted and adapted to be submerged in the metal therein, and cam means connected to the pivoted end of said nozzle for moving said nozzle about its pivot 10 through a curved path to the die mechanism.

19. In a die casting machine adapted to receive die mechanism, a molten metal container, a nozzle adapted to transport metal 15 from said container to the die mechanism, means for moving said nozzle into cooperation with said die mechanism, a cover movable into cooperation with said mechanism, leverage mechanism for actuating said cover, 20 and a counterweight carried by said leverage mechanism.

20. In a die casting machine, die mechanism, a molten metal container, a nozzle adapted to be submerged below the metal 25 in said container for transporting a charge thereof to said die mechanism, pivotal operating mechanism adapted to raise said nozzle from the molten metal up against the under side of said die mechanism, a cover 30 for said die mechanism, a lever for moving the cover having one end connected thereto and a counterweight associated with the other end of the lever.

21. In a die casting machine, die mechanism, a metal pot, a nozzle dipping in said pot, means for moving said nozzle from said pot up into communication with the under side of said die mechanism for transferring the molten metal thereto, a cover for said 40 die mechanism, a lever connected at one end to said cover, a counterweight connected to its other end for insuring the removal of the cover from said die mechanism, and cam means for operating said lever.

45 22. In a die casting machine, a frame, die mechanism carried by said frame, a molten metal container disposed adjacent said die mechanism, a nozzle for conveying molten metal from said container to said 50 die mechanism, and means including a roller

for permitting said container to be slid from its position adjacent the die mechanism.

23. In a die casting machine, a frame, die mechanism carried by said frame, a molten metal container disposed adjacent said die 55 mechanism, a nozzle for conveying molten metal from said container to said die mechanism, a support for the nozzle connected to the frame, and means for permitting said container to be slid from its position adjacent the die mechanism when the nozzle is disconnected from the frame.

24. In a die casting machine, a frame, die mechanism carried by said frame, a molten metal container disposed adjacent said die 65 mechanism, a nozzle for conveying molten metal from said container to said die mechanism, a support for the nozzle connected to the frame, and means for permitting said container to be slid from its position adjacent the die mechanism when the nozzle is disconnected from the frame, said means including a plurality of rollers disposed under said container.

25. In a casting machine, a frame, die mechanism supported by the frame, a molten metal container positioned adjacent the die mechanism, a nozzle in said container having one end pivotally connected to the frame and the other end movable into cooperation 80 with said die mechanism, and means for moving said nozzle connected to its pivotally mounted end.

26. In a casting machine, a frame, die mechanism supported by the frame, a molten metal container positioned adjacent the die mechanism, a nozzle in said container having one end pivotally connected to the frame and the other end movable into cooperation 85 with said die mechanism, and means for moving said nozzle connected to its pivotally mounted end, said means including a lever pivotally mounted on said frame, a link element connecting one end of said lever to said nozzle, and a cam cooperable with the 90 other end of said lever.

In witness whereof, I hereunto subscribe my name this 25th day of July, 1924.

JOHN S. GULLBORG.
